UNITED STATES PATENT OFFICE.

JOHN F. CLEMENT, OF PHILADELPHIA, PENNSYLVANIA.

PNEUMATIC HAMMER.

No. 842,626.

Specification of Letters Patent.

Patented Jan. 29, 1907.

Application filed April 15, 1905. Serial No. 255,800.

To all whom it may concern.

Be it known that I, JOHN F. CLEMENT, a citizen of the United States, residing in the city and county of Philadelphia, State of Pennsylvania, have invented a new and useful Pneumatic Hammer, of which the following is a specification.

My invention consists of a novel construction of a pneumatic impact-tool in which the motive fluid used to drive the piston forward toward the working tool does not pass through the main distribution-valve which controls the admission and exhaust of the motive fluid to the cylinder.

15 It further consists of a novel construction of a main distribution-valve and a novel arrangement of air ports and passages whereby a cushion of live air is formed between the piston and the end of the valve adjacent thereto before the valve changes and the motive fluid is admitted to move the piston forward.

20 It further consists of a novel construction of main distribution and inner and outer auxiliary valves coacting therewith.

It further consists of novel features of construction, as will be hereinafter fully set forth.

Figure 1 represents a longitudinal sectional view of a pneumatic tool embodying my invention, having a portion of the casing removed for clearness of illustration. Fig. 2 represents a longitudinal sectional view having the handle partly broken away. Fig. 3 represents a longitudinal section of a portion of the tool, showing the controlling-valve as being partly open. Fig. 4 represents a longitudinal sectional view of a portion of the tool, showing the valve as being closed and certain of the exhaust-ports open. Fig. 5 represents, on a reduced scale, a longitudinal vertical section, partly broken away, showing the ports and passages through which the motive fluid passes to return the piston and 45 to seat the valve. Fig. 6 represents a perspective view of a portion of the casing, showing the keyway therein. Fig. 7 represents a perspective view of the key. Fig. 8 represents a bottom plan view of a modified form 50 of the controlling-valve. Fig. 9 represents a plan view, partly in section, of the handle-valves, showing the valves as closed. Fig. 10 represents a sectional plan view similar to Fig. 9, but showing the inner regulating-valve as being partly open. Fig. 11 repre-

sents a sectional plan view of the handle-valve, showing both valves in open position.

Similar numerals of reference indicate corresponding parts in the figures.

Referring to the drawings, 1 designates a pneumatic tool, comprising an outer casing or cylinder 2, within which is tightly fitted an inner casing 3. The outer end of the casing is tapered and is provided with a groove 4, in which one end of a spring or clip is adapted to be seated, the other end of said spring contacting with the rivet-set 6 and holding the same in proper relation to the casing 2. 7 designates a handle which is secured to said casing 2 by means of a key 8, which is adapted to fit a keyway or seat 9 in the casing 2. 10 designates a lug near the other end of the key 8 and having an opening therethrough adapted to receive a screw or bolt 11, the threaded end 12 of which engages with a corresponding thread in the sleeve of the handle 7. The key 8 is thicker near the lug and gradually tapers toward one end, and as the slot or keyway 9 corresponds thereto when the bolt 11 is tightened the key 8 will be firmly wedged between the sleeve or head block of the handle and its keyway 9, thus holding the handle at all times in proper relation to the cylinder.

13 designates the inlet for the motive fluid, which is suitably threaded or otherwise adapted to be connected with the base for the motive-fluid supply, which passes therefrom through the port 14 into the chamber of the bushing 15, which latter has an opening or valve-seat 16 therethrough.

17 designates a valve adapted to be seated in the opening 16, which is loosely mounted on a rod 18, which is connected at one end to a valve-rod 19 and has at its other end a regulating-valve 20, which is normally seated in a recess in the valve 17.

21 designates a shoulder on the rod 19, between which and the valve 17 the valve 17 is movable.

22 designates the enlarged end or head of the valve-rod 19, between which and the inner wall of the chamber 23 a spring 24 is interposed, the tension of which normally keeps the valves 17 and 20 closed.

25 designates a manually-operated lever suitably pivoted at 26 and adapted to operate the valve-rod 19 and the valves actuated thereby.

27 designates an air-passage or pressure-

supply duct leading from the opening 16 to the inlet-port 28, which opens into the casing within which the main distribution-valve 29 is adapted to reciprocate and which is composed of two differential areas 30 and 31. The large differential area 31 is adapted to move within the bore 32, while the small differential area 30 is adapted to move within the bore or piston-chamber 33, within which latter a piston 34 is also adapted to reciprocate.

35 designates an annular groove in the area 30 of the valve 29, and 36 designates another groove in said area which extends partly into the larger area 31.

37 designates air-passages leading from the groove 35 into a chamber 38, within which the two auxiliary valves 39 and 40 are adapted to move. The inner auxiliary valve 39 has a reduced end or striker or tappet 41, which has recesses 42 therein and is adapted to closely fit and move in an opening 43 in the bottom of the main valve 29, which latter opening has therein the grooves 44, the use of which will be hereinafter explained. The outer auxiliary valve 40 has an enlarged head 45, which is adapted to be seated at certain times in a recess 46 in the top of the main valve 29.

30 47 designates air-passages in the valve 40, which register at certain times with air-passages 48, which latter extend from the groove 36 into the chamber 38, so as to allow the air back of the auxiliary valves 39 and 40 to escape into the groove 36.

49 designates an air-passage leading from the groove 35 and opening into the chamber 38 at a point just below the inner end of the valve 40, when the enlarged head 45 thereof is seated in the recess 46, so that the valve 39 will be seated at the bottom of the chamber 38 when the air passes through said passage into said chamber 38.

50 designates a passage through which the motive fluid passes to return the piston 34 and having the ports 51 and 52 opening into the interior of the casing.

53 designates an exhaust-passage opening into the interior of the casing at 54 and 55.

50 56 designates an exhaust-passage opening into the casing at 57, 58, and 59, the port 58 being smaller than the port 57, so that when the piston is returned the dead air will all be exhausted and there will be no compression of dead air between the piston and the valve 29.

60 designates a passage through which the air passes to change the valve and having ports 61, 62, and 63 opening into the casing.

64 designates an exhaust-port leading from the interior of the casing to the atmosphere.

The operation is as follows: Having the main valve 29 in the position seen in Fig. 1, the trigger 25 is actuated and the spring-

pressed valve-rod 19 will be depressed and 65 with it the valve 20 secured thereto. The pressure of the motive fluid against the valve 17 will hold the same firmly seated until the shoulder 21 contacts with the bottom of the valve 17, at which time both valves will be 70 moved by the rod 19. As soon as the valve 20 begins to open the live air will rush in and equalize the pressure, which will cause the valve to be very easily regulated. If desired, the rod 18 may be grooved, at 18^X, 75 so that a greater amount of air will pass therethrough. The parts being in the position seen in Figs. 1 and 5, the motive fluid now passes through passage 27 and port 28 into groove 35 through port 52, passage 50, 80 and port 51 underneath the piston and moves the same rearward or toward the handle 7, the air back of the piston exhausting through ports 57 and 58 into passage 56, through port 59, around the groove 36, and 85 through the port 64 into the air. The air will also pass from the groove 35 through the passage 49 into the chamber 38 and acting on the greater area 39 will cause the inner auxiliary valve to be moved to the left or seated 90 in the bottom of said chamber, as in Figs. 1 4, and 5, so that live air cannot pass through the passages 37. As the piston 34 moves rearward the port 61 is uncovered and the main valve will remain seated, owing to the 95 pressure of the air passing from the port 61 and passage 60 and through the port 63 to the enlarged areas 31 and 45 until the piston contacts with the striker or tappet 41, whereupon the inner auxiliary valve 39 will 100 be moved rearward into the position seen in Figs. 2 and 3 and permit the live air to enter through the passages 37, chamber 38, and grooves 42, and thus form a live-air cushion between the end of the piston and the adjacent end of the main valve 29. It will be observed that the ports 42 terminate a short 105 distance from the ends of the striker 41, so that when the latter reaches the position seen in Figs. 2 and 3 a body of air is trapped 110 between the piston and the juxtaposed end of the main valve 29. The main valve 29 will now be moved rearward into the position seen in Fig. 3, and the groove 35 will be 115 out of register with the inlet-port 28. The live air can now pass under the main valve 29, the parts being in the position seen in Fig. 3, and as I have a nearly straight or direct and uninterrupted passage from the inlet in the handle to the piston-chamber 33 the 120 piston is driven forward with great force and a very powerful blow imparted to the shank of the working tool 6. As the piston travels forward the air in front of the piston will exhaust through port 54, passage 53, port 55, 125 annular groove 36 in the main valve 29, and port 64 to the air, since the main valve is still in the position seen in Fig. 3; but as the pis-

ton passes the port 62 live air will enter therein, pass through passage 60 and port 63 behind the valve, so that at the time the piston impacts upon the working tool the valve and its adjuncts will be firmly seated in their forward position, as will be understood from Fig. 5. It will be seen that the passages 47 of the outer auxiliary valve 40 do not normally register with the passages 48 of the main valve 29, which lead to the groove 36 and thence to the exhaust-port 64; but if for any reason the main valve 29 should stick in the cylinder so that the tool would not start the enlarged head 39 of the inner auxiliary valve would coact with the outer auxiliary valve 40 and raise the latter from its seat into the position seen in Fig. 2, so that the passages 47 and 48 would register with each other and the air back of the valve escape around the groove 36 and through the exhaust-port 64 to the atmosphere.

It is apparent that the casings 2 and 3 may be integral, if so desired, and that slight changes may be made in the arrangement of the ports and passages, as well as the proportions of the different areas of the valves, without departing from the spirit of my invention.

The motive fluid does not pass through the valve to move the piston forward, and when the piston moves rearward there is no compression of the exhausting air and the live air will enter with such rapidity that a sufficient cushion will be formed to prevent the piston from ever hitting the bottom of the main valve 29.

In the present embodiment of my invention I have shown the valve mechanism comprising the main valve and the inner and outer auxiliary valve as located directly within the extremity of the tool-cylinder; but it will be apparent that, if desired, changes therein within the scope of my invention may be made.

It will be understood that while I have shown in the present invention the preferred manner of arranging the ports and passages and have omitted from some of the views for the sake of clearness of illustrations certain ports and passages various other modes of applying the principle of my invention may be employed for the mode herein explained, and various changes may therefore be made as regards the mechanism thus disclosed, and I do not, therefore, desire to be restricted in every instance to the exact construction herein shown and described.

Having thus described my invention, what I claim as new, and desire to secure by Letters Patent, is—

1. In a pneumatic hammer, a cylinder adapted to be manually held and having a piston therein and a valve mechanism, comprising a main valve, and a plurality of auxiliary valves, the latter being carried by said

main valve, said valves moving in substantial alinement with said piston.

2. In a pneumatic hammer, a valve mechanism, comprising a main valve having differential pressure areas, and a plurality of inner and outer auxiliary valves, one of said valves being tappet-actuated.

3. In a pneumatic hammer, a valve mechanism, comprising a main valve, and an inner and outer auxiliary valve, said outer valve being operated by fluid-pressure, and said inner valve by its contact with the piston.

4. In a pneumatic hammer, a valve mechanism, comprising a main valve having differential pressure areas, an outer auxiliary valve having differential pressure areas, and an inner auxiliary valve having differential areas, said outer valve being operated by fluid-pressure and said inner valve by its contact with the piston.

5. In a pneumatic hammer, a valve mechanism, comprising a main valve, having differential pressure areas and an inner and outer auxiliary valve, said outer valve being operated by fluid-pressure, and a reduced end or striker on said inner valve, which latter is operated by contact of the piston therewith.

6. In a pneumatic hammer, a valve mechanism, comprising a main valve having differential pressure areas and an inner and outer auxiliary valve, said outer valve having differential pressure areas, air-passages extending from the rear of said outer valve through the smaller area thereof, and air-passages through said main valve with which said outer valve-passages register, when said outer valve is actuated, said inner valve being operated by contact with the piston, and said outer valve by fluid-pressure.

7. In a pneumatic hammer, a valve mechanism, comprising a main valve having differential pressure areas, and an inner and outer auxiliary valve, said outer valve having differential pressure areas, a recess at the outer end of said main valve in which the larger area of said outer valve is adapted to be seated, exhaust-passages through said main valve, and exhaust-passages through said outer valve adapted to register therewith at certain times, said outer valve being operated by fluid-pressure, and said inner valve by contact with the piston.

8. In a pneumatic hammer, a valve mechanism, comprising a main valve, having differential pressure areas, and an inner and outer auxiliary valve, said outer valve being operated by fluid-pressure, said inner valve being operated by contact with the piston, and means for exhausting the air from the larger area of the main valve through said outer valve and said main valve.

9. In a pneumatic hammer, a valve mechanism, comprising a main valve and an inner and outer auxiliary valve, said outer valve

being operated by fluid-pressure, said inner valve having differential areas, recesses in the smaller area thereof, air-passages through the main valve controlled by the larger area of said inner valve, whereby when the latter is actuated by contact with the piston, a live-air cushion is formed between the main valve and the piston, and a passage through the main valve for live air which latter seats said inner valve.

10. In a pneumatic hammer, a valve mechanism, comprising a main valve having differential areas and an inner and outer auxiliary valve, an inner and outer groove around said main valve, said inner groove controlling the admission of air to return the piston, and said outer groove controlling the exhaust, said outer valve being operated by fluid-pressure and said inner valve by contact with the piston.

11. In a pneumatic hammer, a valve mechanism, comprising a main valve having differential pressure-areas, and an inner and outer auxiliary valve, each of said valves having differential pressure areas, said outer valve being operated by fluid-pressure, said inner valve by its contact with the piston, and inlet and exhaust ports controlled by said main valve, said inlet-port when open permitting motive fluid to pass directly to the piston-chamber without traversing said main valve.

12. In a pneumatic hammer, a valve mechanism, comprising a main valve, and an inner and outer auxiliary valve carried thereby, each of said valves having differential pressure areas, said outer valve being operated by fluid-pressure, said inner valve being moved forwardly by live air and rearwardly by its contact with the piston, inlet and exhaust ports controlled by said main valve, exhaust-ports controlled by said outer valve, said inlet-port admitting air to the cylinder under said main valve when said inlet-port is open, and means for forming a live-air cushion between the piston and the adjacent end of said main valve.

13. In a pneumatic hammer, the combination of a cylinder and piston, a valve mechanism, a tappet-actuated valve forming a part of said mechanism, and means actuated by said tappet for creating a live-air cushion between said piston and valve mechanism.

14. In a pneumatic hammer, a cylinder, a piston therein, a valve mechanism comprising a main distribution-valve of differential areas, an outer auxiliary valve and an inner auxiliary valve, and means on said inner auxiliary valve for creating a live-air cushion between the piston and said main distribution-valve, whereby the latter is prevented from being damaged by said piston.

15. In a pneumatic hammer, a cylinder, a piston therein, a valve mechanism therefor,

said valve mechanism comprising a main distribution-valve, an outer auxiliary valve and an inner auxiliary valve, means for admitting live air to the piston to drive the latter forward without said air traversing said valve mechanism, and means on said inner auxiliary valve for creating a live-air cushion between the piston and main valve.

16. In a pneumatic hammer, a cylinder adapted to be manually held and having a hammering-piston therein, the forward end of said cylinder being adapted for the reception of the shank of a working tool, and a valve mechanism for controlling the movement of said piston and comprising a main valve located in substantial alignment with said piston, and an inner and outer auxiliary valve carried by said main valve.

17. In a pneumatic hammer, a cylinder adapted to be manually held and having a hammering-piston therein, the forward end of the latter being adapted for the reception of the shank of a working tool, and a valve mechanism comprising a main valve having differential pressure areas and a plurality of auxiliary valves carried by said main valve.

18. In a pneumatic hammer, a cylinder adapted to be manually held and having a hammering-piston therein, the forward end of the latter being adapted for the reception of the shank of a working tool, a valve mechanism comprising a main valve having differential pressure areas and a plurality of auxiliary valves carried by said main valve, one of said auxiliary valves being operated by fluid-pressure and the other by its contact with said piston.

19. In the valve mechanism of a pneumatic hammer, a tappet-actuated valve beneath which motive fluid enters to actuate the piston and means actuated by the tappet thereof for creating a live-air cushion between the piston and valve mechanism.

20. In a pneumatic hammer, a cylinder having a hammering-piston therein, a valve mechanism therefor comprising a main valve, and an inner and outer auxiliary valve carried thereby, said inner valve having a striker thereon operated by contact of said piston therewith.

21. In a pneumatic hammer, a cylinder having a hammering-piston therein, a valve mechanism therefor comprising a main valve, and an inner and outer auxiliary valve carried thereby, said inner valve being operated by its contact with the piston, and means for exhausting the air from the larger area of the main valve through said outer valve and main valve.

22. In a pneumatic hammer, a cylinder having a hammering-piston therein and a valve mechanism therefor, comprising a main valve and a plurality of auxiliary valves carried thereby; one of said auxiliary valves

being tappet-actuated and means controlled by the tappet for creating a live-air cushion between said piston and valve mechanism.

23. In a pneumatic hammer, a cylinder; a piston therein and a valve mechanism therefor comprising a main distribution-valve, an outer auxiliary valve, an inner auxiliary valve and a striker projecting from the latter through said main valve and having a groove therein to permit the creation of an air-cushion between said piston and main valve.

24. The combination of a cylinder having a hammering-piston therein, a grasping-handle on said cylinder, a manually-operated valve in said handle and a valve mechanism for said cylinder comprising a main valve, a tappet-actuated inner auxiliary valve, an outer auxiliary valve and means actuated by the tappet for creating a live-air cushion between said piston and valve mechanism.

25. In a pneumatic hammer, a cylinder having a hammering-piston therein and an inlet-port, and a valve mechanism comprising a main valve controlling said port, and a plurality of auxiliary valves, one of said auxiliary valves being tappet-actuated, the other of said auxiliary valves being fluid-actuated,

and said main valve being above said inlet-port when in raised position.

26. In a pneumatic hammer, a cylinder having a differential bore provided with a hammering-piston, and a valve mechanism comprising a main valve engaging said bore and having differential pressure areas, and a plurality of auxiliary valves carried by said main valve, one of said valves being tappet-actuated.

27. In a pneumatic hammer, a cylinder having an inlet-port therein and a valve mechanism controlling said port at one side of which latter the motive fluid enters to advance the piston, said valve mechanism comprising a main distribution-valve, an outer auxiliary valve, and an inner auxiliary tappet-valve.

28. In a pneumatic hammer, a valve mechanism, comprising a main valve and a plurality of inner and outer auxiliary valves, the two latter being arranged in alinement with each other.
